DESIGN FOR A STORE FRONT

Chester A. Patterson, Milwaukee, Wis.

Application January 22, 1945, Serial No. 117,543

Term of patent 14 years

(Cl. D13—1)

To all whom it may concern:

Be it known that I, Chester A. Patterson, a citizen of the United States, residing at Milwaukee, in the county of Milwaukee and State of Wisconsin, have invented a new, original, and ornamental Design for a Store Front, of which the following is a specification, reference being had to the accompanying drawing, forming part thereof.

I claim:

The ornamental design for a store front, as shown.

CHESTER A. PATTERSON.
